United States Patent Office.

JOHN LANGHAM, JR., OF PHILADELPHIA, PENNSYLVANIA.

Letters Patent No. 81,652, dated September 1, 1868.

IMPROVEMENT IN TOOL FOR SLITTING BOARDS.

The Schedule referred to in these Letters Patent and making part of the same.

TO ALL WHOM IT MAY CONCERN:

Be it known that I, JOHN LANGHAM, Jr., of Philadelphia, in the county of Philadelphia, and State of Pennsylvania, have invented a new and useful Improvement in Tools for Cutting or Slitting Thin Boards; and I do hereby declare that the following is a full, clear, and exact description thereof, which will enable others skilled in the art to make and use the same, reference being had to the accompanying drawings, forming part of this specification, in which—

Figure 1 represents a longitudinal sectional elevation of my improved device, and

Figure 2 represents a plan view of the same.

Similar letters of reference indicate like parts.

The object of this invention is to provide a simple and convenient tool for expeditiously cutting thin boards, such as are used for the backs of picture-frames.

It consists of a cutter or knife, secured vertically to a hinged holder, which is suspended on a sliding stock arranged in ways, resting at each end upon suitable supports, which may be secured to a bench, so as to maintain the said ways sufficiently above the bench to admit the board to be cut to be passed under the same in front of the cutter, which being pushed forward by the operator, will sever the board. A spring is connected to the stock of the cutter to retract it.

A represents ways, secured at each end to the cross-piece B. A sliding cutter-stock, C, is arranged to slide back and forth on the said ways, and provided with a handle, D, and a bracket, E, to which the tool-holder F is hinged.

G represents the tool, which is secured to the holder by any suitable means.

H represents a retracting-spring, which is secured to the tool-stock, and to the front cross-piece B.

The implement thus constructed may be secured to a bench by the spurs I, or by any other suitable means, and the thin material to be cut may be passed under it, with one edge gauged against the back piece B, when, by shoving the tool forward, the stuff will be cut off square to the edge, in any desired lengths, and in a much more expeditious manner than by the common method of sawing, or by cutting against a rule, by a knife in the hand.

Having thus described my invention, I claim as new, and desire to secure by Letters Patent—

The combination of the sliding stock C, provided with a cutter, with the ways A and supporting-pieces B, substantially as and for the purpose described.
